TO CARY MANUFACTURING COMPANY, OF BROOKLYN, NEW YORK, A CORPORATION OF NEW YORK.

BAND-TIGHTENER.

1,367,121.

Specification of Letters Patent.

Patented Feb. 1, 1921.

Application filed March 9, 1918, Serial No. 221,570. Renewed November 7, 1919. Serial No. 336,471.

To all whom it may concern:

Be it known that we, SPENCER C. CARY and VINCENT RAGONA, both citizens of the United States, and residents of the city of New York, borough of Brooklyn, county of Kings, and State of New York, have invented a certain new and useful Band-Tightener, of which the following is a specification.

10 This invention is an implement for stretching a binder, tie or band around a shipping package of one form or another, such as a box, case, shooek, crate, etc.

Among the objects of the invention are, 15 first, to facilitate the operation of initially engaging the implement with the binder or tie preliminarily to stretching the latter around the shipping package; second, to stretch the binder or tie while it remains in 20 contact with the surface of the package, thereby obviating slack in said binder or tie upon the removal of the implement; third, to operate each gripper by means located conveniently to the attendant and 25 thus dispense with the manipulation of separate parts, such as detachable wedges; fourth, to secure such engagement between the gripper and the binder or tie that the latter cannot slip through the gripper when 30 the implement is manipulated for applying tension to said binder sufficiently to compress the boards or slats into tight contact with end members of the shipping package, and, finally, to simplify the construction, in- 35 crease the efficiency and render the implement economical to manufacture.

Generally speaking, the invention embodies a plurality of heads, a screw spindle operable for effecting a relative movement 40 between said heads, and grippers carried by said heads, each gripper being novel in construction.

Other features and advantages of the invention will appear from the following detailed description taken in connection with the drawings, wherein—

Figure 1 is a plan view illustrating the stretching tool or implement applied in an operative position upon a shipping package

for the purpose of tightening the major portion of a binder or tie into tight contact with the boards or slats thereof.

Fig. 2 is a cross section on an enlarged scale and in the plane indicated by the dotted line 2—2 of Fig. 1.

Fig. 3 is a cross section in the plane of the dotted line 3—3 of Fig. 2, illustrating one of the grippers.

The implement shown in the drawings embodies in its construction heads A, B, a guide rod C, and a screw spindle D. The heads A and B are similar in construction, each being preferably cast in a single piece. Each head is enlarged at a a' and provided with an opening b in the enlarged part a , and an opening b' in the enlarged part a' , the opening b' being threaded. The head is constructed at the end opposite to the enlargement a with parallel ears c c' , the latter being integral with the material of the head.

The guide rod C is fitted at one end in the opening b of head B, said end of the rod being made fast with the head B by a pin d or other suitable means. The rod fits loosely in the opening b of the head A, said rod C coöperating with the spindle D in retaining the heads A and B in parallel relation. Said spindle D is provided with two screw threads, one being a right-hand thread and the other a left-hand thread, and said threaded parts of the spindle engage with the threads in the openings b' of the heads A and B, whereby rotative movement of the spindle imparts traveling movement simultaneously to the heads A and B in order to effect relative movement between the heads. The spindle D is provided at one end portion with a suitable operating means, such as the hand crank d' .

The under side of each head adjacent to the ears c c' is formed with a ledge constituting a fixed jaw E which extends across the space between the ears c c' , the exposed face of said fixed jaw E being toothed or serrated, as indicated at e in Fig. 2.

Coöperating with each head A and B is a movable jaw F, the same consisting of a

plate of hardened metal of a size to fit snugly in the space between the ears *c*, *c'*. The movable jaw is positioned in opposing or facing relation to the fixed jaw *E*, and to 5 adapt said movable jaw to operate efficiently in gripping the wire the lower edge portion of said jaw is grooved at *f* and toothed or serrated at *f'*. Said jaw *F* is attached to the head with which it is associated, preferably by means of a pin *g* which connects the upper part of the jaw pivotally to the head. 10

It will be noted that the jaw *E* is provided on the under side of the head and that the 15 movable part of the jaw *F* is at the under side of the head, whereby an opening or space is left between the jaws *E* and *F* next to the shipping package upon which the implement is adapted to rest. The two jaws 20 of each head are normally opened by a spring *G*, one form of which is shown in Fig. 2 as a coiled spring housed within an opening *h* of the head *A* or *B*, one end portion of said spring being received in a recess *h'* provided 25 in the corresponding movable jaw *F*. The grippers formed by the jaws *E* and *F* of the two heads *A* and *B* are adapted to be closed upon the binder or tie by the action of cam levers *I*, the same being attached to the heads 30 *A* and *B* and extending outwardly therefrom so as to be within convenient reach of the operator. Each part *I* is formed with a cam head *i* which is positioned in the space between the ears *C* *C'*, said cam head being 35 provided with a cam surface *i'* adapted for frictional contact with the movable jaw *F*. The cam head is pivoted to and between the ears *c* *c'* by a cross pin *j*, and unitary with this cam head is a handle *j'*, it being preferred to make the cam head and the handle 40 in one piece.

The implement is adapted to be placed upon a shipping package, as indicated in Fig. 1, at *L*, so that said implement can be engaged with a binder *O* while the latter remains in contact with said package *L*. With the jaws *E* and *F* of the two grippers pressed open by the springs *G*, heads *A* and *B* of the implement will receive the end portions 45 of the binder *O* between the serrated faces *e* *f'* of said jaws, whereby the end portions of the binder *O* are adapted to be engaged by the grippers without lifting the binder from contact with the package for an appreciable 50 distance. The operator should press down on the handles of the cam levers *I* for the purpose of moving the jaws *F* toward the jaws *E*, and thus the two grippers engage tightly with the binder *O* so as to leave the 55 end portions of the binder free or unconfined between the heads *A* and *B*, as illustrated in Fig. 1. With the grippers tightly engaged with the binder the operator proceeds to 60 apply rotative movement to the screw spindle

D, thus drawing the heads *A* and *B* toward 65 each other and tightening the binder *O* around the shipping package.

The implement of this invention operates to apply very considerable strain or pull to the binder in order that the latter will be 70 drawn tightly upon the shipping package and in a manner to compress the slats or boards of said package into engagement tightly with the end members of said package; in fact, the binder can be drawn so 75 tightly upon the soft wood of the package as to embed said binder into the material of the package, as indicated at *o* in Fig. 1. With the implement operated to draw the binder tightly, the end portions of said binder are 80 manipulated easily and freely by the operator and without relaxing tension upon the major part of the binder, for the reason that the end portions are free and loose between the heads *A* and *B*, as shown in Fig. 85 1. The loose end portions of the binder are anchored to the shipping package by suitable means, one form of said anchoring means being a seal *P* indicated in the upper part of Fig. 1. The operation of fastening 90 the binder having been completed, the operator now manipulates the levers *I* *I'* to release the gripping jaws from the binder, whereupon the tool or implement is lifted from contact with the case so that it can 95 be re-used in fastening the other binder to the package.

Having thus fully described the invention, what we claim as new and desire to secure by Letters Patent is:

100

1. A device of the class described embodying a plurality of heads, means for imparting relative movement thereto, and grippers carried by the heads for engagement with a binder or tie while the latter is in contact 105 with a shipping package, each gripper embodying a fixed jaw, a movable jaw, and a jaw-operating lever separate from and co-operating with the movable jaw, said lever being movable on an axis extending parallel 110 to the faces of the gripping jaws and at a right angle to the median line of the head on which the gripper is mounted.

2. A device of the class described embodying a plurality of heads, means for effecting 115 relative movement between them, and grippers positioned on the heads for engagement with a binder or tie lying beneath said device, each gripper comprising a fixed jaw, a movable jaw, and a cam lever separate from 120 said movable jaw and contacting therewith, said cam levers being movable on axes extending parallel to the faces of the gripping jaws and at a right angle to the median line of the head by which the gripper is carried.

3. A device of the class described embodying a plurality of heads each provided with gripper-supporting ears and with a fixed

125

5 jaw, means for imparting relative movement to said heads, a movable gripper jaw pivoted between the ears of each head in position for coöperation with the fixed jaw, and cam levers fulcrumed to said ears of the heads in position for contact with the movable gripper jaws, each cam lever being movable on an axis extending parallel to the faces of said jaws and at a right angle to the median line 10 of the head by which said gripper jaws and cam lever are carried.

4. In a device of the class described, a plurality of heads each provided at an end portion with spaced ears and on its underside 15 with a fixed jaw, combined with a movable jaw pivoted to said ears of each head, a cam lever pivoted to said ears of each head and positioned for contact with said movable jaw, each cam lever being separate from 20 said movable jaw and said cam lever being movable on an axis extending parallel to the faces of said jaws and at a right angle to the median line of the head, means for separating said jaws, and means for imparting 25 relative movement to said heads.

5. A device adapted to rest upon a shipping package for stretching a binder or tie embodying a plurality of heads each provided at one end with spaced ears and with 30 a jaw extending between said ears, movable jaws pivoted to the ears, said first and second named jaws being positioned to open relatively to the underside of each head, cam levers pivoted to the ears of said heads 35 and extending outwardly therefrom into accessible positions, each cam lever being separate from the movable jaw with which it coacts and being movable on an axis extending parallel to the faces of said movable jaw 40 and at a right angle to the longitudinal axis of the head, said cam levers coöoperating with the movable jaws, and means for effecting relative movement between the heads.

6. A device adapted to rest upon a shipping package for stretching a binder or tie embodying a plurality of heads each provided at one end with spaced ears and with 45 a jaw extending between said ears, movable jaws pivoted to the ears, said first and second named jaws being positioned to open relatively to the underside of each head, springs acting against the movable jaws for normally separating the latter relatively to the movable jaws, cam levers pivoted to the 50 ears, and means for effecting a relative movement between the heads.

7. A device adapted to rest upon a shipping package for stretching a binder or tie embodying a plurality of heads each provided at one end with spaced ears and with 55 a jaw extending between said ears, movable jaws pivoted to the ears, said first and second named jaws being positioned to open relatively to the underside of each head,

and said jaws being provided with roughened gripping faces, cam levers pivoted to the ears for coöperation with the movable jaws, springs positioned for contact with the movable jaws to separate the latter from the fixed jaws, and means for effecting relative 65 movement between said heads, each cam lever being separate from the movable jaw with which it coacts and being movable on an axis extending parallel to the faces of said movable jaw and at a right angle to the 70 longitudinal axis of the head.

8. In a device of the class described, means for gripping a binder embodying a head provided with a fixed jaw, a movable jaw pivoted to said head and positioned in coöperative relation to the fixed jaw, a spring for opening the movable jaw relatively to the fixed jaw, and a cam lever coöperating with said movable jaw, said cam lever being pivoted to the head separately from the movable jaw and said cam lever being movable on an axis extending parallel to the faces 85 of the jaws and at a right angle to the longitudinal axis of the head.

9. In a band stretching device, a cross-head provided with a gripping face positioned substantially at a right angle to the longitudinal axis of said cross head, a movable jaw pivoted to said crosshead for movement on an axis extending approximately 90 parallel to the plane of said gripping face, said movable jaw being provided with a gripping face in opposing relation to the gripping face of the crosshead, means for moving the pivoted jaw relatively to the 95 gripping face of the crosshead, and a cam lever separate from the crosshead, said cam lever being fulcrumed on the crosshead in a position for actuating the movable jaw.

10. In a band stretching device, the combination of a plurality of crossheads each provided with a gripping face the plane of which is substantially perpendicular to the longitudinal axis of said crosshead, a plurality of movable jaws, one of said jaws 100 being pivoted to each crosshead and said jaw being provided with a gripping face in opposing relation to the gripping face of the crosshead, said gripping faces of the crossheads and of the jaws being normally 105 separated at the face of the stretching device adapted to rest into contact with a package to be bound, a plurality of cam levers, one to each crosshead, said cam lever being fulcrumed to the crosshead for movement on 110

an axis positioned approximately parallel to the plane of the gripping faces, a guide rod coöperating with the crossheads, and a screw for imparting movement to said crossheads.

11. In a band stretching device, the combination of a plurality of crossheads each of which is bifurcated and provided within

said bifurcation with a gripping face the plane of which is substantially perpendicular to the longitudinal axis of said crosshead, a plurality of movable jaws one of which is positioned within the bifurcation of each crosshead, each jaw being pivoted to said crosshead, an incased spring acting to press each movable jaw with respect to the gripping face of the crosshead, and a plu-

rality of cam levers, each pivoted within the bifurcation of one crosshead and positioned for contact with one of said movable jaws.

In testimony whereof we have hereunto signed our names this 8th day of March, 1918.

SPENCER C. CARY.
VINCENT RAGONA.
